UNITED STATES PATENT OFFICE.

IRVING JENSEN, OF WEST BRANCH, IOWA.

WATER-HEATER.

1,073,687.

Specification of Letters Patent. Patented Sept. 23, 1913.

Application filed April 3, 1913. Serial No. 758,627.

To all whom it may concern:

Be it known that I, IRVING JENSEN, a citizen of the United States, residing at West Branch, in the county of Cedar and State of 5 Iowa, have invented certain new and useful Improvements in Water-Heaters, of which the following is a specification.

My invention relates to water heaters and has particular reference to apparatus of this 10 character adapted to be submerged in the water held within a bath tub, tank or other receptacle, and to be removed therefrom after the water is properly heated.

An important object of my invention is to 15 provide a heater of the above mentioned character, which is compact, simple in construction, and cheap to manufacture.

A further object of the invention is to 20 provide apparatus of the above mentioned character having novel means for heating the oil or other liquid fuel before the same is supplied to the burner.

A further object of this invention is to 25 provide novel means to hold the entire apparatus properly submerged in the water, and prevent the same from being upset therein.

Other objects and advantages of this invention will be apparent during the course of the following description.

30 In the accompanying drawings forming a part of this specification, and in which like numerals are employed to designate like parts throughout the same, Figure 1 is a central vertical longitudinal sectional view 35 through the entire apparatus, showing the same in its submerged condition, and, Fig. 2 is a plan view of the same.

In the drawings, wherein for the purpose 40 of illustration, I have shown a preferred embodiment of my invention, the numeral 3 designates a tank or other receptacle, which is partially filled with water 4, to be heated. My heater comprises an upstanding body portion 5, having curved ends 6, which preferably carry handles 7. The body portion 5 is provided with a bottom 8, as shown.

The numerals 9 and 10 designate transverse partitions or walls, disposed within the body portion 5 adjacent the inner ends 50 of the curved ends 6. These transverse partitions 9 and 10 form with the curved ends 6, upstanding end passages 11 and 12 respectively, as shown.

The numeral 13 designates a horizontal 55 oil or liquid fuel supply tank, which is formed of portions of the body portion 5,

portions of the transverse partitions 9 and 10, a bottom 14 and a top 15. This top is provided with an opening which is normally closed by a removable plug 16, whereby oil 60 may be fed into the tank 13. The top 15 has at one end a stationary extension 15^a closing the outlet passage 12, and at its opposite end a pivoted perforated extension or lid 15^b, to be moved to open and closed positions. The pivoted extension or lid 15^b is 65 perforated to allow of the inlet of air into the inlet passage 11, but prevents the free passage of rain therein, when the apparatus is used out of doors.

The numeral 15^c designates a preferably 70 downwardly swinging door, to normally close one end of the burner chamber, but permitting of access thereto when opened, for the purpose of lighting the burner or 75 the like.

Connected with the bottom 14 of the tank 13, is an oil supply pipe 17, provided with a cut-off valve 18, the stem 19 of which extends through an opening formed in the 80 partition 9 into the passage 11, as shown. Arranged below the pipe 17 is a burner pipe 20, connected therewith, as shown. This burner pipe is horizontally arranged and has its free end closed by a cap 21. The 85 burner pipe is provided between its ends with a suitable number of perforations 22, to allow of the escape of the oil, which is ignited at this point. Below the burner pipe 20 is a horizontal partition or wall 23, 90 suitably attached at its ends to the transverse partitions 9 and 10. This horizontal partition 23 is provided near its center with an upstanding tube 24, the upper end of which is formed open and serves to support 95 the burner pipe 20 and to supply air to the same adjacent the perforations 22. The horizontal partition 23 is spaced from the bottom 8 of the body portion 5, for providing a horizontal air passage 25, having communication with the upstanding air passage 11 through an opening 26, as shown.

Disposed above the supply pipe is a horizontal partition or wall 27, suitably connected with the transverse partitions 9 and 10 and forming a chamber 28. This chamber 28 has no communication with the upstanding passages 11 and 12 and is provided with a suitable number of openings 29, whereby the cold water enters the chamber 110 and is free to circulate into and out of the same.

The products of combustion generated within the burner chamber 30, pass through an opening 31 and discharge into the upstanding passage 12. This upstanding passage 12 is provided at its upper end with a stack 32, carried by the extension or section 15^a, as shown.

I prefer to construct the body portion 5 and associated elements of sheet metal, owing to the fact that this material is very light and will readily transmit heat to the water.

The numeral 33 designates a heavy weight, which weighs much more than the body portion 5 and elements contained therein. This weight has a lower convex surface, as shown at 34, and an upper horizontal surface which engages the bottom 8, and is suitably connected therewith. The function of this weight is to hold the entire apparatus properly submerged in the water and to provide a very low center of gravity, whereby the apparatus will always remain in its upright position and cannot be accidentally knocked over.

The operation of the apparatus is as follows:—The tank 3 is partially filled with the water to be heated. The heater is then placed within the water, whereby the same is submerged, as shown. The valve 18 is now open, whereby the oil will escape through the perforations 22, at which point the oil is ignited. When igniting the oil, the pivoted door 15^a is swung to its open position, whereby the operator may insert his arm through the passage 11 into the burner chamber 30, to light the burner. The amount of the oil admitted to the burner is of course controlled by proper manipulation of the valve 18. During the operation of the apparatus, air is drawn downwardly through the passage 11 into the horizontal passage 25, and passes through the tube 24 to be supplied to the oil being burned at the perforations 22. Heated gases and products of combustion pass from the chamber 30 into the passage 12 and finally discharge through the stack 32. Attention is called to the fact that the oil

passing through the supply pipe 17 is thoroughly heated before the same discharges through the perforations 22. The oil within the tank 13 is slightly heated but this temperature is maintained comparatively low by the water circulating through the chamber 28.

It is to be understood that the form of my invention herewith shown and described is to be taken as a preferred example of the same, and that certain changes in the shape, size and arrangement of parts may be resorted to without departing from the spirit of the invention or the scope of the subjoined claims.

Having described my invention, I claim:—

1. In apparatus of the character described, a main shell, heat generating means mounted therein, and a weight formed of a section of a sphere and attached to the lower end of the main shell and having its engaging surface smooth and regular whereby the weight will serve as a pivot upon which the apparatus may turn in all directions and as means for preventing the accidental tilting of the apparatus.

2. In apparatus of the character described, a main shell adapted to be submerged in water while occupying a horizontal position; of means forming vertical inlet and outlet passages at the opposite ends of the main shell; means for dividing the main shell into an upper fuel holding chamber, and intermediate water circulating chamber, and a lower heating chamber, all of which are arranged horizontally and extend for the entire distance between the inlet and outlet passages; a burner mounted within the lower heating chamber; and a conduit connecting the burner with the upper fuel holding chamber.

In testimony whereof I affix my signature in presence of two witnesses.

IRVING JENSEN.
